UNITED STATES PATENT OFFICE

157,373

ELECTRICAL CONTROL UNIT

George C. Izenour, New Haven, Conn.

Application September 29, 1947, Serial No. 141,648

Term of patent 14 years

(Cl. D26—13)

To all whom it may concern:

Be it known that I, George C. Izenour, a citizen of the United States of America, residing at New Haven, in the county of New Haven and State of Connecticut, have invented a new, original, and ornamental Design for an Electrical Control Unit, of which the following is a specification, reference being had to the accompanying drawings, forming a part thereof, in which:

Figs. 1 and 2 are, respectively, a top plan view and a front elevation of an electrical control unit, showing my new design;

Fig. 3 is a vertical sectional view thereof;

Fig. 4 is a front perspective view thereof; and

Fig. 5 is a front perspective view thereof at a somewhat smaller scale, the dotted lines appear-

ing in these figures being for illustrative purposes only.

What I claim is:

The ornamental design for an electrical control unit, substantially as shown and described.

GEORGE C. IZENOUR.
